HINGE

Filed March 16, 1932

UNITED STATES PATENT OFFICE

LOUIS W. MORLEY, OF TRENTON, NEW JERSEY, ASSIGNOR TO C. V. HILL & CO., INC.,
OF TRENTON, NEW JERSEY, A CORPORATION OF NEW JERSEY

HINGE

Application filed March 16, 1932. Serial No. 599,257.

This invention relates to hinges, and its main object is to provide a simple, strong, durable and efficient joint between the hinge leaves whereby the leaves are hingedly united and limited in their swinging movement relative to each other.

The invention further has for its object to provide a hinge for use on refrigerator doors and for other like uses, which is durable and inexpensive in construction and substantially proof against sagging, and which possesses a pleasing and attractive form and appearance.

The invention consists of the features of construction, combination and arrangement of parts, hereinafter fully described and claimed, reference being had to the accompanying drawing, in which:—

Fig. 1 is a front elevation of a hinge embodying my invention, and

Fig. 2 is a horizontal transverse section of the same, showing the closed and open positions of the swinging leaf in full and dotted lines, respectively.

In carrying my invention into practice I provide a hinge comprising a pair of leaves 1 and 2, cast or molded of suitable metal or a metal alloy, and provided or not, as required, with a finishing coating or plating. The leaves 1 and 2 are respectively designed for application to a wall 3 and a door 4 of a refrigerator or other receptacle, as indicated in dot and dash lines in Fig. 2, the leaves being provided with openings 5 for the passage of suitable fastenings to secure them in position.

The leaf 1 is provided with a pair of outwardly and horizontally projecting and vertically spaced knuckle flanges 6 having alined pin receiving openings 7 therein, and also having openings 8, arranged inwardly of and in transverse alinement with the openings 7 to receive a stop pin 9 extending between the flanges. The flanges 6 are of substantial size and character so that the hinge member 2 and part to which it is attached may be stably supported from the hinge member 1.

The hinge member 2 is provided with a centrally disposed reduced tongue 10, projecting beyond its inner edge and having an outer end portion 11 projecting rearwardly at sub-

stantially a right angle to the plane of the link 2 and terminating in a stop flange 12. The tongue 10 and a portion of the leaf 2 in alinement therewith are formed with an outwardly projecting reinforcing offset 13, of less depth than the width of the tongue so as to provide top and bottom flanges 14. These flanges 14 intersect knuckle flanges 15 formed on and extending inwardly from the part 11 of the tongue and projecting rearwardly beyond the rear face of the leaf 2. These knuckle flanges 15 are provided with openings 16 for passage of a pintle pin 17, which also projects through the openings 7 of the knuckle ears 6, thus hingedly connecting the leaf 2 with the leaf 1 for swinging movements to a closed position in which the leaf 2 is parallel with the leaf 1 and to an open position in which the leaf 2 lies at an angle of 90° or more to the leaf 1.

It will be seen that the construction described provides a solid and substantial mounting for the leaf 2 on the leaf 1, as the knuckle plates 6 and 15 are of generous area and thickness so as to provide staunch supports for the pivot pins 17, which may accordingly be made of large diameter to ensure a firm and secure pivotal connection of the leaves with one another. It will also be seen that the described form and arrangement of the pivot pin 17 and the stop pin 9 provides ample space for the turning movements of the knuckle flanges in the swinging movements of the leaf 2, as well as the swinging movements of the stop flange 12, and that

said stop flange 12 in the closed position of the leaf 2 substantially closes the space between the knuckle flanges 6 at the outer side and, when the leaf 2 is swung fully open to the dotted line position shown in Fig. 2, the flange 12 is brought into abutting engagement with the stop pin 9 to positively limit the outward swinging movement of the leaf 2. It will further be seen that the described construction of the knuckle flanges 15, and the provision of the offset portion 13, enables said flanges 15 to be made of comparatively large size so that such parts of the hinge leaf 2 will give a high degree of strength, stability and firmness to the joint connection. A

hinge construction is thus provided which is simple, durable, solid and substantial, as well as ornamental, and which embodies reliable and effective means for limiting the movement of the leaves relative to each other.

The hinge device disclosed is especially designed for use on refrigerators and other like receptacles, but it is to be understood that the invention is not limited thereto, as the 10 hinge, in the form disclosed, and in permissible modified forms, may be designed for use upon various kinds and types of receptacles for hingedly supporting doors and other like closures. It is also to be understood 15 that, while the structure shown is preferred, changes in the form, proportions and details of construction may be made, within the scope of the appended claims, without departing from the spirit or sacrificing any of 20 the advantages of the invention.

What I claim is:—

1. A hinge comprising a pair of leaves, one leaf having a pair of knuckle flanges extending forwardly therefrom in spaced relation 25 and a stop pin carried by said flanges, and the other leaf having at one end thereof a tongue bent rearwardly substantially at right angles thereto and provided with lateral knuckles extending between and pivoted to 30 the said knuckle flanges and having a stop flange for engagement with the said stop pin at the limit of swinging movement of the second-named leaf.

2. A hinge comprising a pair of leaves, 35 one leaf having a pair of knuckle flanges extending forwardly therefrom in spaced relation and a stop pin carried by said flanges, and the other leaf having at one end thereof a centrally disposed tongue bent rearwardly 40 substantially at right angles thereto and terminating in a stop flange and also having flanges projecting inwardly and laterally from said tongue and between the said knuckle flanges, and a pintle pin connecting 45 the knuckle flanges of the leaves, the said stop flange of the second-named leaf being adapted for engagement with the said stop pin at the limit of swinging movement of the second-named leaf.

3. A hinge comprising a pair of leaves, one leaf having a pair of forwardly projecting knuckle flanges provided with pin receiving openings and a stop pin extending between 55 said flanges on the inner side of and in transverse alinement with said openings, and the other leaf having a centrally disposed tongue provided with an outwardly projecting reinforcing boss, said tongue being bent rearwardly at its free end substantially at right 60 angles to the leaf and terminating in a stop flange, said boss being of less depth than the tongue and forming top and bottom reinforcing flanges having lateral enlargements providing knuckle flanges having pin receiving 65 openings at the inner side of the free end

of the tongue projecting between the knuckle flanges of the first-named leaf, and a pintle pin engaging the openings in the knuckle flanges of the leaves and pivotally connecting said leaves, the said stop flange of the second-named leaf being adapted to engage the stop pin of the first-named leaf to limit the relative swinging movement of the leaves.

In testimony whereof, I affix my signature.

LOUIS W. MORLEY.
